Sloan Vitreous China Washdown Urinal reference [Oct. 17, 2019] found online [Oct. 17, 2019]—https://www.sloan.com/commercial-bathroom-products/urinals/sloan-vitreous-china/su-7409.**Primary Examiner* — Brandon M Rosati*Assistant Examiner* — John A Voytek(74) *Attorney, Agent, or Firm* — Banner & Witcoff, Ltd.(57) **CLAIM**

The ornamental design for a urinal, as shown and described.

DESCRIPTION

FIG. 1 is a top, front, right perspective view of a urinal showing our new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

In the drawings, the broken lines depict unclaimed portions of the urinal.
